UNITED STATES PATENT OFFICE.

CALEB D. PAGE, OF GREELEY, COLORADO, ASSIGNOR TO PAGE PORTABLE BUILDINGS COMPANY, OF GREELEY, COLORADO, A CORPORATION OF COLORADO.

BUILDING CONSTRUCTION.

1,154,203.

Specification of Letters Patent. Patented Sept. 21, 1915.

Application filed November 4, 1910. Serial No. 590,606.

To all whom it may concern:

- Be it known that I, CALEB D. PAGE, a citizen of the United States, residing at Greeley, county of Weld, and State of Colorado, have
5 invented an Improvement in Building Construction, of which the following description, in connection with the accompanying drawing, is a specification, like characters on the drawing representing like parts.
- 10 This invention relates to building construction and has for its object to provide features of construction by which a light and yet strong building can be inexpensively built.
- 15 In order to give an understanding of my invention I will first describe a selected embodiment thereof after which the novel features will be pointed out in the appended claims.
- 20 Figure 1 of the drawings shows a fragmentary sectional view through the sill and lower portion of the wall of a building embodying my invention; Fig. 2 is a detail of the door frame; Fig. 3 is a detail showing
25 the manner of fastening the flitch-beam posts to the sill; Fig. 4 is a detail showing the manner of fastening one of the studs to the sill; Fig. 5 is a side view of one of the studs of the building; Fig. 6 is an enlarged
30 section through a portion of the wall of a building embodying my invention.
- The present invention relates particularly to a building in which the posts and girders are combination elements formed partly of metal and partly of wood, the metal and wood portions of these elements being so arranged that the metal gives the desired strength and stiffness to them and the wood furnishes means for attaching sheathing.
- 35 In the drawings I have illustrated at 6 one of the sills of a building which is herein shown as having an I-beam construction. This sill has secured to each side of the web 9 thereof a wooden element or filling piece 35, these filling pieces being secured to the I-beam in any suitable way.
- The frame of the building is formed of posts and longitudinal members or girders which, as stated above, are constructed to give a maximum stiffness and yet provide means for readily attaching sheathing thereto. These studs and girders are preferably of a modified flitch beam construction and each comprises a shaped sheet metal member 19 and two wooden members 20 and
40
- 21 fitting the angles of the shaped member. The member 21 is of a size to exactly fill its angle so that the side 22 thereof comes flush with one of the angles of the shaped member. The wooden member 20, 60 however, is of such a size that the face 23 thereof projects beyond the metal member, said projecting face furnishing a support to which the sheathing may be nailed or screwed. The three members of any stud 65 or girth are fastened together by bolts or rivets 256. Any desired number of these flitch beam studs and girders may be used. The studs are secured at their lower ends to the sills of the building and at their upper ends to the plate, and in order to provide for attaching the stud to the sills and plate, I form the shaped member 19 of such studs with the laterally-extending feet 24 which overlie and are secured 70 to the flanges of the sills. The same construction may be used for securing the studs to the plates 13, or said studs may be simply bolted to the vertical flange of said plates. These flitch beam studs are 75 designated generally by 25 and the horizontal members or girders are designated generally by 26. The girders are preferably situated on the outside of the vertical members or studs and extend from one end to the other of the building. The girders and studs are so disposed relative to each other that the flat sides come adjacent each other so that the faces 23 of the studs face inwardly, while the corresponding faces 23 of the girders 26 face outwardly. The studs 25 and girders 26 are fastened together by screws or bolts 257.
- The wall of the building is formed by an exterior sheathing 27 which is secured to 95 the faces 23 of the girders 26 and an interior sheathing 28 which is secured to the faces 23 of the studs 25. This sheathing, both interior and exterior, may be made of any suitable material, but will preferably be sheet metal and can be either nailed or screwed directly to the wooden members 20 of the studs and girders. In order to make the building warmer, I may employ a lining 29 100 of paper or some other lining material, such, for instance, as linofelt, which will be preferably interposed between the studs 25 and the girders 26. This lining forms a dead air space between itself and the outer sheathing 27 and another space between itself and the 110

inner sheathing 28, which inner space may be used for ventilating the building, and for this purpose I have shown the inner sheathing 28 as provided with openings 45 near 5 the floor through which the vitiated air may escape into the space between the sheathing.

The floor 34 of the building is sustained partly by the flanges of the sills and partly by the wooden supporting members 35 which 10 are bolted to the sills, said members 35 furnishing supports to which the floor may be nailed (see Figs. 1 and 6).

In order to provide the building with doors, I propose to form the door frame of 15 channel-iron members 50, as shown in Fig. 2, and in order to secure the door posts to the top 7 of the sills 6 I propose to bend one of the wings of each post laterally to form a foot 52 which rests on the top of the 20 sill, the other wing extending down and overlapping the side of the filling member 34 and being secured thereto in any suitable way.

While I have illustrated herein one embodiment of my invention I do not wish 25 to be limited to the constructional features shown.

Having fully described my invention, what I claim as new and desire to secure 30 by Letters Patent is:—

1. In building construction, the combination with a base frame, of studs rising therefrom and each comprising a sheet metal member having a L shape throughout its length, two wooden members extending from one end to the other of said metal member and fitting the angles thereof, means permanently securing said wooden members to the L shaped member and 40 sheathing secured to one of the wooden members.

2. In building construction, the combination with a base frame, of studs rising therefrom and each comprising a sheet 45 metal member having a L shape, two wooden members fitting the angles of and permanently secured to the L shaped member, one wooden member extending beyond the L shaped member, and sheathing 50 secured to said projecting wooden member.

3. In building construction, the combination with a base frame, of studs rising therefrom and each comprising a sheet 55 metal member having a L shape, two wooden members fitting the angles of the L

shaped member and rivets extending through both wooden members and the body of the L shaped member for permanently connecting said parts, one wooden member 60 extending beyond the L shaped member, and sheathing secured to the projecting wooden member of each stud.

4. In building construction, the combination with a base frame, of studs rising 65 therefrom, girths secured to the studs, each girth being a unitary structure formed of a L shaped sheet metal member, two wooden members fitting the angles of the L shaped member and rivets extending 70 through both wooden members and the central portion of the L shaped member for permanently connecting them together, and sheathing secured to the wooden members of the girths.

5. In building construction, the combination with a base frame, of studs rising therefrom, girths on the outside of the studs and secured thereto, said studs and girths 75 each being formed of a sheet metal L shaped member and two wooden members fitting the angles of the L shaped member, the wooden member on the outside of each girth and on the inside of each stud projecting beyond the sheet metal member, an 80 interior sheathing secured to the projecting wooden member of each stud, and an exterior sheathing secured to the projecting wooden member of each girth.

6. In building construction, the combination with a base frame, of studs rising 85 therefrom, girths on the outside of the studs and secured thereto, said studs and girths each being formed of a sheet metal L shaped member and two wooden members fitting the angles of the L shaped member, the wooden member on the outside of each girth and on the inside of each stud projecting beyond the sheet metal member, an 90 interior sheathing secured to the projecting wooden member of each stud, and an exterior sheathing secured to the projecting 100 wooden member of each girth, and a lining interposed between the girths and studs.

In testimony whereof, I have signed my 105 name to this specification, in the presence of two subscribing witnesses.

CALEB D. PAGE.
